GRINDING MACHINE

Oiva E. Hill, West Boylston, Mass., assignor to
 Norton Company, Worcester, Mass., a corporation of Massachusetts

Application January 10, 1950, Serial No. 137,834

13 Claims. (Cl. 51—89)

1

The invention relates to grinding machines, and more particularly to a grinding machine for simultaneously grinding the opposed edges of a workpiece.

One object of the invention is to provide a simple and thoroughly practical grinding machine for grinding the opposed spaced edges of a workpiece. Another object is to provide a grinding machine with a pair of opposed spaced grinding wheels which are arranged simultaneously to grind partial cylindrical surfaces on opposed spaced edges of a workpiece, such as, a turbine or jet motor blade. Another object of the invention is to provide a turret-type work holder to convey workpieces to and from a grinding position. Another object of the invention is to provide a turret-type work holder for conveying workpieces to and from a grinding position which serves also to support the workpiece during a grinding operation. Another object of the invention is to provide a work driving mechanism for rotating the workpiece relative to the turret when it is in an operative grinding position to grind partial cylindrical faces on opposite edges of a workpiece.

A further object is to provide a hydraulically operated turret locating and work driving head which is arranged to locate the work turret precisely in a predetermined indexed position, and to oscillate the workpiece to be ground between the opposed spaced operative faces of a pair of spaced rotatable grinding wheels. Another object is to provide a transversely movable hydraulically operated slide for supporting the work turret and the turret locating work driving head. Other objects will be in part obvious or in part pointed out hereinafter.

The invention accordingly consists in the features of construction, combinations of elements, and arrangements of parts, as will be exemplified in the structure to be hereinafter described and the scope of the application of which will be indicated in the following claims.

In the accompanying drawings in which is shown one possible embodiment of the mechanical features of this invention:

Fig. 1 is a plan view of the improved grinding machine;

Fig. 2 is a rear elevation of the grinding machine;

Fig. 3 is a fragmentary vertical sectional view, on an enlarged scale, taken approximately on the line 3—3 of Fig. 1, showing the work turret and associated parts;

Fig. 4 is a fragmentary horizontal sectional

view, on an enlarged scale, taken approximately on the line 4—4 of Fig. 3, through one of the work holders and associated parts;

Fig. 5 is a fragmentary horizontal sectional view, on an enlarged scale, of the work supporting and driving mechanism;

Fig. 6 is an elementary side elevation, on an enlarged scale, of the work turret and driving mechanism therefor;

Fig. 7 is a fragmentary vertical sectional view, on an enlarged scale, taken approximately on the line 7—7 of Fig. 1, through the wheel slide feeding and adjusting mechanism;

Fig. 8 is a fragmentary vertical sectional view, on an enlarged scale, taken approximately on the line 8—8 of Fig. 1, through the wheel slide base feeding and adjusting mechanism;

Fig. 9 is a fragmentary vertical sectional view, on an enlarged scale, taken approximately on the line 9—9 of Fig. 1, through the wheel slide nut and screw feeding mechanism;

Fig. 10 is a combined hydraulic and electrical diagram;

Fig. 11 is a fragmentary vertical sectional view, taken approximately on the line 11—11 of Fig. 4, showing the mechanism for actuating the work driving spindle;

Fig. 12 is a diagrammatic showing of the workpiece and its movement relative to the grinding wheels; and

Figure 13 is a fragmentary plan view, on an enlarged scale, showing the opposed grinding wheels and the workpiece with fragments of the work supports shown in section.

As illustrated in the drawings the grinding machine embodying this invention comprises a base 10 having a transversely movable wheel slide base 11 which is arranged to slide transversely on a flatway 12 and a V-way 13. The wheel slide base 11 serves as a support for a wheel slide 14 which is arranged to slide on a flatway 15 and a V-way 16 formed on the upper surface of the wheel slide base 11. The wheel slide 14 is provided with a rotatable wheel spindle 17 which is journaled in bearings (not shown) and serves as a support for a grinding wheel 18. Any suitable driving mechanism may be provided for rotating the wheel spindle 17 and the grinding wheel 18 such as for example an electric motor 19 mounted on the upper surface of the wheel slide 14. The motor 19 is provided with a multiple V-groove pulley 20 which is connected by multiple V-belts 21 with a multiple V-groove pulley 22 mounted on the end of the wheel spindle 17.

The base 10 also supports a second wheel slide

2

55

base 31 on a flatway 32 and a V-way 33 for a transverse adjustment relative thereto. The wheel slide base 31 serves as a support for a wheel slide 34. A flatway 35 and a V-way 36 are provided between the wheel slide base 31 and the wheel slide 34 to facilitate a transverse adjustment of the wheel slide 34 relative to the base 10 of the machine. The wheel slide 34 is provided with a rotatable wheel spindle 37 which is journaled in bearings (not shown) and serves as a support for a grinding wheel 38. A similar driving mechanism is provided for the spindle 37 and the grinding wheel 38 comprising an electric motor 39 mounted on the wheel slide 34. The motor 39 is provided with a multiple V-groove pulley 40 which is connected by multiple V-belts 41 with a multiple V-groove pulley 42 mounted on the end of the wheel spindle 37.

A feeding mechanism is provided for adjusting the wheel slide base 31 transversely relative to the base 10 comprising a rotatable feed screw 45 (Fig. 8) which is journaled in bearings 46 and 47 mounted in the base 10 of the machine. The wheel slide base 31 is provided with a depending half nut 48 which meshes with or engages the feed screw 45. A gear 49 is mounted on the left hand end of the feed screw 45. The gear 49 meshes with a gear 50 rotatably supported on a shaft 51. A manually operable feed wheel 52 is provided for manually imparting a rotary motion to the feed screw 45 to facilitate adjusting the wheel slide base 31 and the grinding wheel slide 34 as desired.

A similar feeding mechanism is provided between the wheel slide base 31 and the grinding wheel slide 34 comprising a feed screw 55 which is journaled in bearings 56 and 57 mounted in the wheel slide base 31. The wheel slide 34 is provided with a depending half nut 58 which meshes with or engages the feed screw 55. A bevel gear 59 is mounted on the left hand end of the feed screw 55 which meshes with a bevel gear 60 (Fig. 9) mounted on the end of a rotatable shaft 61. The shaft 61 is journaled in bearings 62 and 63 (Fig. 7). A manually operable feed wheel 64 is mounted on the left hand end of the shaft 61 to facilitate a manual rotation of the feed screw 55 to facilitate adjusting the wheel slide 34 relative to the wheel slide base 31.

A similar nut and screw feeding mechanism is interposed between the wheel slide base 11 and the base 10 which is actuated by a manually operable feed wheel 67. This mechanism is identical with that shown in detail in Fig. 8 and described above, consequently it has not been illustrated or described in detail. A similar nut and screw feeding mechanism is interposed between the wheel slide base 11 and the wheel slide 14 to facilitate adjustment of the wheel slide 14 relative to the wheel slide base 11. This mechanism is actuated by means of a manually operable feed wheel 68. This feeding mechanism is identical with that illustrated in Figs. 7 and 9 and described above, consequently it has not been shown and described in detail.

As shown in Fig. 1 the grinding wheel spindles 17 and 37 are angularly arranged to facilitate a shoulder grinding operation on a workpiece. The peripheries of the grinding wheels 18 and 38 are frusto-conical in shape and present opposed operative faces for grinding opposed parallel faces on opposite sides of a workpiece. The upper faces of the wheels 18 and 38, as shown in Fig. 1 are beveled at right angles to the main face of the wheels so that the workpiece may be trav-

ersed relative thereto to grind a shoulder thereon.

A turret-type work holder is provided comprising a work turret 70 which is rotatably mounted on a shaft 71 in vertically arranged bearing brackets 72 and 73. The bearing brackets 72 and 73 are fixedly mounted on a transversely movable slide 74 (Fig. 2). The slide 74 is provided with a dovetailed slideway which mates with a correspondingly shaped slideway formed on the base 10. The shaft 71 is fixedly mounted relative to the brackets 72 and 73.

The work turret 70 is provided with a plurality of work holding devices arranged for successively conveying workpieces to the grinding wheels before a grinding operation has been completed.

As illustrated in Fig. 3, the turret wheel 70 is provided with a plurality of radially arranged work rotating holders 80, 81, 82 and 83 which are arranged to support workpieces 84, 85, 86 and 87 for successive grinding operations. All of the work holding devices are identical in construction, consequently only one of these devices has been illustrated in detail in Fig. 4. The work holding device 80 comprises a rotatable spindle 88 journaled in bearings 89 mounted within the turret wheel 70. The other end of the device 80 is provided with a spindle 90 which is journaled in bearings 91 which are mounted within the turret 70. A work supporting arbor 92 extends between the spindle 90 and the spindle 88 and is fixedly mounted thereon. A spring pressed plunger 93 is contained within the spindle 88. A second slidably mounted plunger 94 is also contained within the spindle 88 and is arranged to ride upon a stationary cam 95 which is fixedly mounted on the shaft 71. A small diameter relatively light compression spring 96 is interposed between the spring pressed plunger 93 and the plunger 94. Similarly a relatively heavy compression spring 97 surrounds the spring 96 and is interposed between the spring pressed plunger 93 and the plunger 94. The relatively light compression spring 96 serves to facilitate a loading operation whereas the relatively heavy compression spring 97 is actuated by the plunger 94 to lock a workpiece on the arbor 92 during a grinding operation.

The left hand end of the spring pressed plunger 93 is provided with a beveled face 98. When it is desired to insert a workpiece into operative position on the arbor 92, the right hand end workpiece 84 is moved into engagement with the beveled face 98 of the spring pressed plunger 93 and the plunger 93 is moved toward the right until the head 99 of the workpiece may be dropped into a mating aperture 100 formed adjacent to the left hand end of the arbor 92.

As shown in Fig. 3, the high point of the cam 95 is arranged to move the plunger 94 outwardly to compress the spring 97 and thereby to lock the workpiece 84 in operative position on the arbor 92 during a grinding operation.

In order to grind a predetermined partial cylindrical surface on the opposed edges of the workpiece 84 when the turret 70 moves the arbor 92 and the spindles 88 and 90 into an operative grinding position, a spindle driving mechanism is provided. As illustrated in Fig. 4, a slidably mounted sleeve 110 is keyed within a cylindrical aperture 111 formed within a portion of the turret 70. A compression spring 112 serves normally to exert a pressure on the sleeve 110 tending to move it toward an extreme left hand end position in which position an internal gear 113 formed within the sleeve 110 meshes with an ex-

ternal gear 114 formed on the left hand end of the spindle 90. The gears 113 and 114 serve normally to hold the arbor 92 so that the workpiece 84 lies in a position at substantially right angles to its grinding position. A suitable mechanism is provided for unlocking the spindle 90 and rotating it through an arc of approximately 90° to generate a partial cylindrical surface on opposed spaced edges of the workpiece 84.

The work rotating mechanism may comprise a rotatable spindle 115 which is journaled in bearings 116 and 117 mounted within a transversely movable slide 118. The slide 118 is preferably arranged so that the axis of the spindle 115 is axially aligned with the spindle 90 when the turret wheel is indexed into successive operative positions. A slidably mounted plunger 120 is contained within the spindle 115. A compression spring 121 serves normally to urge the plunger 120 toward the right (Fig. 4). The plunger 120 is provided with a frusto-conical end 122 which is arranged to engage a correspondingly shaped internal frusto-conical surface 123 formed within the right hand end of the spindle 90. When the slide 118 is moved toward the right from the position indicated in Fig. 4 to the position indicated in Fig. 5, the conical surface 122 engages the internal frusto-conical surface 123 and serves to precisely align the turret wheel 70 to position the work holding arbor 92 and its supporting spindles 88 and 90 in a predetermined grinding position. As the slide 118 is moved toward the right (Figs. 4 and 5), a collar 124 carried by the spindle 115 engages the left hand end face of the sleeve 110 and moves it toward the right against the compression of the spring 112. This movement of the sleeve 110 slides the internal gear 113 toward the right out of mesh with the external gear 114 and at the same time moves an internal gear 125 formed within the collar 124 into mesh with the external gear 114 on the spindle 90. In this position of the parts, it will be readily apparent that a rotary motion of the spindle 115 will be transmitted through the mechanism above described to impart a rotary motion to the spindles 90 and 88.

A fluid pressure mechanism is provided for moving the slide 118 to and from an operative position. This mechanism as shown in Fig. 3 may comprise a cylinder 130 which is fixedly mounted on the slide 118. The cylinder 130 contains a piston 131 which is connected to one end of a piston rod 132. The other end of the piston rod 132 is connected to a bracket 133 formed integral with the transversely movable slide 74. When fluid under pressure is passed through a pipe 135 into the cylinder 130, the cylinder 130 and the slide 118 move downwardly (Fig. 10) or move toward the right (Fig. 4) to move the work driving spindle 115 and its associated parts into an operative position to impart a rotary motion to the spindle 90. A pipe 134 is connected to the other end of the cylinder 130. To facilitate controlling the movement of the slide 118 into an operative position, a throttle valve 136 is provided in the pipe line 134. A ball check valve 137 is provided for bypassing fluid around the throttle valve 136 when the slide 118 is moved toward an inoperative position.

A suitable fluid pressure mechanism is provided for imparting a rotary motion to the spindle 90. This mechanism may comprise a cylinder 140 mounted on the slide 118. A piston 141 is provided within the cylinder 140 and is connected to one end of a piston rod 142. The other end of

the piston rod 142 is fixedly connected to an arm 143, the other end of which is fastened to the left hand end of a slidably mounted rack bar 144 (Fig. 11). The rack bar 144 meshes with a gear 145 which is keyed on the left hand end of the spindle 115 (Figs. 4 and 5). When fluid under pressure is passed through a pipe 148 into the cylinder 140, the piston 141 together with the rack bar 144 are moved toward the right into the position illustrated in Figs. 10 and 11. Similarly when fluid under pressure is passed through a pipe 149 into the cylinder 140, the piston 141 together with the rack bar 144 are moved toward the left (Figs. 10 and 11) to impart a rotary motion to the driving spindle 115 and the work spindle 90 so as to impart a rotary motion to the work supporting arbor 92 and the workpiece 84. In order to control the rate of movement of the piston 141 and thereby to control the rotary motion of the spindles, a throttle valve 150 is provided to regulate fluid flowing through the pipe 148. A ball check valve 147 is provided to permit fluid to bypass the throttle valve 150 to allow the piston 141 to move at a rapid rate during its movement toward the right (Figs. 10 and 11).

The hydraulic mechanism just described serves to rotate the workpiece for a grinding operation. The workpiece such as a jet blade 84 is positioned on the work supporting arbor 92 when the arbor 30 is in a vertical position. In this position the blade is positioned as shown in dotted lines 84a (Fig. 12) with its cross sectional axis lying in a plane normal to the axis of the work turret 70. The movement of the piston 141 serves to rock the blade 84 from position 84a into position 84b to grind a partial cylindrical surface 151 and 152 on opposed spaced edges of the blade 84. The edge portion of the blade 84 to be ground is longer than the width of the operative faces of the 40 grinding wheels 18 and 38, consequently it is desirable to provide a suitable traversing mechanism for causing a relative longitudinal movement between the blade 84 and the grinding wheels 18 and 38 while the blade is in the horizontal position as illustrated in Fig. 12.

A fluid pressure mechanism is provided for traversing the transversely arranged slide 74 to cause a relative longitudinal movement between the blade 84 and the grinding wheels 18 and 38. This mechanism may comprise a cylinder 155 (Fig. 10) which contains a slidably mounted piston 156. The piston 156 is connected to one end of a piston rod 157. The right hand end portion of the piston rod 157 is provided with a screw threaded portion 158. The threaded portion 158 of the piston rod 157 passes through a clearance hole in a bracket 159 depending from or fixedly mounted on the underside of the slide 74. A pair of nuts 160 and 161 serve to lock the bracket 159 and the slide 74 on the threaded portion 158 of the piston rod 157. It will be readily apparent from the foregoing disclosure that by manipulation of the nuts 160 and 161, the position of the bracket 159 and the slide 74 may be varied relative to the piston 156 to facilitate setting up the grinding machine.

In order to provide an adjustment for the stroke of the slide 74, the threaded portion 158 of the piston rod 157 passes through a clearance hole 162 formed in a lug 163 which is fixedly mounted relative to the base 10. Pairs of spaced nuts 164 and 165, each having lock nuts associated therewith, are provided to serve as tops to limit the stroke of the piston 156 and the slide 157.

Fluid under pressure may be admitted through

a pipe 166, through a ball check valve 167 and a pipe 168 into the left hand end of the cylinder 155 to move the piston 156 and the slide 74 toward the right. During the movement of the piston 156 toward the right, fluid within the right hand end chamber of the cylinder 155 exhausts through a pipe 169. During the movement of the piston 156 toward the right, an idle stroke is imparted to the slide 74. When fluid under pressure is admitted through the pipe 169 into the right hand end chamber of the cylinder 155 to cause an operative stroke of the piston 156 and the slide 74 toward the left, fluid exhausting through the pipe 168 passes through a throttle valve 170 and thus bypasses the ball check valve 167. By adjusting the throttle valve 170, the rate of movement of the slide 74 may be readily controlled as desired.

A ball check valve 171 is provided in the pipe line 169 to allow free exhaust of fluid through the pipe 169 from the right hand end of the cylinder 155 during the return stroke of the slide 74.

It is desirable to provide a delayed action of the movement of the slide 74 to allow the slide 118 to move into an operative position to connect the driving spindle 115 with the work spindle 90 and to allow the piston 141 to move toward the left (Fig. 10) so as to rotate the spindle 90 to move the workpiece from position 84a through approximately 90° into position 84b (Fig. 12) so as to grind the partial cylindrical faces 151 and 152 on the workpiece 84 before fluid is passed through the pipe 169 into the right hand end of the cylinder 155 to start the traversing movement of the slide 74. This is preferably accomplished by means of a fluid pressure actuated sequence valve 172 (Fig. 10) which is arranged so that when fluid is passed into the pipe 169, it first passes through a pipe 173 to move the piston of the sequence valve 172 toward the right against the compression of the spring within the right hand end of the valve 172. After the valve piston has moved toward the right, fluid under pressure in the pipe 169 may then pass through a valve chamber 174, thus bypassing the ball check valve 171 and into the right hand end of the cylinder 155 to start the traversing movement of the slide 74. This traversing movement of the slide 74 continues until the nut 165 engages the lug 163 thus limiting the movement of the work relative to the grinding wheels 18 and 38 so as to grind a predetermined shoulder portion on opposite sides of the blade 84. Due to the fact that less fluid under pressure is required to move the pistons 131 and 141, than is required moving the sequence valve 172, these pistons move and complete their operative strokes before the valve piston moves a sufficient distance to uncover the valve chamber 174 thus delaying the admission of fluid under pressure to other right hand end of the cylinder 155.

A suitable indexing mechanism is provided for indexing the work turret 70 to convey workpieces to and from a grinding position. This mechanism is preferably hydraulically operated and comprises a fluid motor 175 which is supported by a bracket or frame 176 which is in turn fixedly mounted on the transversely movable slide 74. The fluid motor 175 is preferably a constant displacement piston type fluid motor, such as that manufactured by Vickers Inc., of Detroit, Michigan and such as is shown in the prior United States Patent No. 2,404,309 to J. A. Martin dated July 16, 1946. The motor 175 serves to drive a worm 177 (Fig. 6) which meshes with a worm

gear 178 mounted on a shaft 179. The shaft 179 is journalled in a bracket 180 fixedly mounted on the transverse slide 74. A gear 181 is fixedly mounted on the shaft 179 and meshes with a gear 182 which is fixedly mounted on the work turret 70. When fluid under pressure is passed through a pipe 185 (Fig. 10) to the fluid motor 175, the turret wheel 70 will be rotated in a clockwise direction (Fig. 3) or in a counter clockwise direction (Fig. 6). During this movement, fluid is exhausted from the motor through a pipe 186.

In order to control the indexing movement of the work turret 70, a notched index plate 190 (Figs. 6 and 10) is provided on the shaft 179. The index plate 190 is provided with a plurality of notches 191, 192, 193 and 194. A vertically movable index pawl is normally held in engagement with the periphery of the index plate 190 by means of a compression spring 196. In order to withdraw the index pawl automatically to facilitate an indexing movement of the turret 70, a hydraulically operated mechanism is provided comprising a cylinder 197 having a slidably mounted piston 198 therein. When fluid under pressure is passed through a pipe 199, the piston 198 is moved downwardly to withdraw the pawl 195 from engagement with the notch in the index plate 190. The withdrawal of the index pawl 195 is controlled automatically in a manner to be hereinafter described.

When the pawl 195 is moved downwardly to an inoperative position, it engages the actuating plunger of a normally open limit switch LS2. During the movement of the pawl 195 to an operative position, a detent 201 which is fixedly mounted on the pawl plunger 195 engages and rocks a rock arm 202. The rock arm 202 is pivotally supported on a stud 203. The detent 201 during its upward movement under influence of the compression spring 196 rocks the rock arm 202 in a counterclockwise direction to momentarily depress an actuating plunger 204 of a normally open limit switch LS3.

To facilitate automatic operation of the machine, a cam plate 210 is fixedly mounted on the shaft 179. The plate 210 is provided with a plurality of cams 211, 212, 213 and 214 which are fixedly mounted in the periphery thereof. As the plate 210 rotates during an indexing movement of the work turret 70, the cams 211, 212, 213 and 214 engage the actuating roller of a normally closed limit switch LS1 and open the switch for purposes to be hereinafter described.

To facilitate removal of a workpiece from the supporting arbor, a work ejecting plunger 218 is provided. The plunger 218 is supported by a bracket 219 which is fixedly mounted on the slide 74. The axis of the plunger 218 is positioned so that it is in axial alignment with the axis of the work spindle 90 when the work turret 70 has been indexed through 180°. A compression spring 220 (Fig. 3) serves normally to hold the plunger 218 in an inoperative or left hand end position. When it is desired to remove a workpiece from the supporting arbor, the plunger 218 is moved toward the right (Fig. 3). Movement of the plunger 218 toward the right engages and moves a slide rod 222 which is slidably keyed within a central aperture within the spindle 90 toward the right. Movement of the rod 222 toward the right (Fig. 5) serves to move the workpiece 84 toward the right against the compression of the spring 96. This movement of the workpiece 84 toward the right continues for a sufficient distance so that the head 99 of the

workpiece 84 moves sufficiently toward the right so that it is out of the aperture 100. In this position the workpiece 84 may be readily swung upwardly and thereby removed from supporting engagement on the work supporting arbor 92. This unloading operation takes place when the workpiece is indexed through 180° from the grinding position.

A hydraulically operated control system is provided for controlling the cycle of operation of the various mechanisms above described so that except for manual loading of the workpiece into position on the work turret 70, the machine functions automatically after it is initially started. A fluid pressure actuated control valve 225 is provided for controlling the admission of fluid under pressure to the fluid motor 175. The shifting movement of the control valve 225 is controlled by a pilot valve 226 which is in turn actuated in a manner to be hereinafter described by a solenoid S2. The control valve 225 comprises a slidably mounted valve member 227 which is shifted endwise by means of fluid under pressure from the pilot valve 226. A similar fluid pressure actuated control valve 228 is provided for regulating the exhaust of fluid from the fluid motor 175 to facilitate controlling the rate of movement of the motor during an indexing movement. The control valve 228 is actuated by a pilot valve 229 which is in turn actuated by means of a solenoid S4. The control valve 228 includes a slidably mounted valve member 230 which is shifted longitudinally by means of fluid under pressure as governed by the pilot valve 229. A fluid pressure actuated control valve 231 is provided for controlling the admission of fluid through the pipe 199 to the pawl actuating cylinder 197. The valve 231 is controlled by a pilot valve 232 which is in turn actuated by a solenoid S1. The control valve 231 includes a slidably mounted valve member 233 which is moved endwise by means of fluid under pressure as controlled by the pilot valve 232. A fluid pressure actuated control valve 234 is provided for controlling the admission of fluid to and the exhaust of fluid from the cylinders 130, 140 and 155. The control valve 234 is controlled by a pilot valve 235 which is in turn actuated by a solenoid S3. The valve 234 includes a slidably mounted valve piston 236 which is shifted longitudinally by means of fluid under pressure as governed by the pilot valve 235.

A fluid pressure system is provided for supplying fluid under pressure to the various mechanisms of the machine. This system may comprise a reservoir 240 which is preferably formed within the base 10 of the machine. Fluid is pumped from the reservoir 240 through a pipe 241 by means of a motor driven fluid pump 242 and is forced under pressure through a pipe 243 to the control valves 225, 228, 231 and 234. An adjustable relief valve 244 is provided in the pipe line 243 which facilitates maintaining a constant operating pressure within the system by allowing any excess fluid under pressure to escape through a pipe 245 into the reservoir 240.

The operation of this machine will be readily apparent from the foregoing disclosure. When it is desired to start a grinding cycle, a manually operable switch 250 is closed to energize the solenoid S1 which shifts the pilot valve 232 so that fluid under pressure shifts the valve member 233 toward the right thereby passing fluid under pressure from the pipe 243 through the pipe 199 to withdraw the index plunger 195 from

engagement with the index plate 190. As the index plunger 195 moves to an inoperative position, it depresses the actuating plunger 200 of the limit switch LS2 to close the switch and thereby to energize the solenoid S2 which serves to shift the valve member 227 toward the right (Fig. 10) so that fluid under pressure passes through the pipe 185 to start the motor 175 and thereby to start an indexing movement of the turret wheel 70 to present the next workpiece into a grinding position.

The solenoid S4 is deenergized so that when fluid under pressure passes through the pipe 185 to start the index motor 175, fluid exhausts therefrom through the pipe 186, through control valve 228 and passes out through a slow speed throttle valve 249 and through the exhaust pipe 253 into the reservoir 240. The indexing movement of the turret starts slowly at a rate governed by the throttle valve 249.

As soon as the indexing movement of the turret starts, the cam 211 on the plate 210 rides off the actuating roller 215 of the limit switch LS1 thereby allowing the limit switch LS1 to close. The closing of the limit switch LS1 serves to energize the solenoid S4 to shift the pilot valve 229 and thereby to shift the valve member 230 toward the right (Fig. 10) so that fluid exhausting from the motor 175 through the pipe 186 may exhaust from the control valve 228 through a pipe 251 and through a throttle valve 252 and through an exhaust pipe 253 into the reservoir 240. The throttle valve 252 serves to control the speed of the motor 175 so as to control the speed of the indexing movement of the turret wheel 70.

The rotary indexing movement of the turret 70 continues at a relatively rapid rate as governed by throttle valve 252 until the turret 70 approaches an indexed position. As the turret 70 approaches an indexed position, the cam 214 on the plate 210 engages the actuating roller 215 and opens the limit switch LS1 which breaks a circuit to deenergize the solenoid S4 thereby causing the control valve 228 to shift into the position illustrated in Fig. 10, so that fluid exhausting from the motor 175 through the control valve 228 passes through the slow speed throttle valve 249 so as to slow down the turret 70 before the index pawl 195 moves into engagement with the next notch 192 in the index plate 190. By manipulation of the throttle valves 249 and 252, the slow and fast movement of the turret may be independently adjusted as desired.

The rotary indexing movement of the turret wheel 70 continues until the index plate 190 rotates through approximately 90° and the index pawl 195 is moved into engagement with the notch 192 by the released compression of the spring 196. Movement of the pawl 195 into operative engagement with the notch 192 serves to open the limit switch LS2 thereby deenergizing the solenoid S2 which shifts the valve member 227 toward the left into the position illustrated in Fig. 10 to stop the flow of fluid under pressure to the motor 175.

When the plunger 195 moves upwardly into operative engagement with the notch 192, the limit switch LS3 is momentarily closed in a manner above described which serves to start a time relay 254 in motion. This time relay may be of any standard variety such as for example a Microflex time relay such as manufactured by the Signal Electric Corporation of Moline, Illinois. The time relay serves to control the duration of the grinding cycle. Setting in motion

of the time relay 254 serves to energize the solenoid S3 to shift the pilot valve 235 so as to cause the valve member 236 to shift toward the right (Fig. 10) so that fluid under pressure in the pipe line 243 may pass through the pipe 169, 5 through the pipe 135 to move the slide 118 upwardly thereby engaging the work driving spindle in a manner above described. At the same time fluid under pressure in the pipe 169 passes through the pipe 149 to move the piston 141 and the rack bar 144 toward the left to impart a rotary motion to the work spindle and the workpiece 84 to rotate the workpiece through approximately 90° from position 84a into position 84b to grind partial cylindrical surfaces 151 and 152 on opposed edges of the workpiece 84. At this time fluid under pressure in the pipe 169 builds up pressure within the pipe 173 to open the sequence valve 172 so that fluid under pressure within the pipe 169 may pass into the cylinder 155 to cause a transverse movement of the slide 74 to shift the workpiece 84 longitudinally so that the grinding wheels 18 and 38 will grind the remainder of the opposed sides of the workpiece and also will engage and grind shouldered surfaces 84a and 84b, as shown in Fig. 13. As above described the sequence valve is arranged to delay the action of the piston 156 until the pistons 131 and 141 have completed their movements. The grinding operation continues with the wheels in engagement with the shoulders 84a and 84b until the time delay relay 254 operates after a predetermined cycle to deenergize the solenoid S3. Deenergizing the solenoid S3 shifts the pilot valve 235 into the position illustrated in Fig. 10 so that the valve member 236 moves toward the left into the position illustrated, in which position fluid under pressure is admitted through the pipe 166 to cause a return movement of the piston 141 which serves to swing the workpiece from position 84b into position 84a to complete the grinding of the arcuate surfaces on the edge portion of the workpiece 84 adjacent to the shoulder faces 84a and 84b thereon. After the workpiece has swung from position 84b into position 84a, the slide 118 is moved rearwardly to disengage the driving spindle from the work spindle thereby to stop rotation of the work at which time fluid under pressure passing through the pipe 166 entering the cylinder 155 causes a transversely movable slide 74 to move to an inoperative position ready for the next indexing operation. As above explained workpieces are loaded into the machine in the work holder at the top of the turret wheel 70 (Fig. 3). On the next indexing movement of the turret 70 the workpiece moves into a grinding position. After a second indexing movement the workpiece 84 which has been ground will be indexed through 180° into position so that it may be removed from the work supporting arbor 92 by actuation of the ejecting plunger 218. It will be readily apparent from the foregoing disclosure that once the cycle of operation is started by actuation of the manually operable switch 250 successive workpieces are automatically ground to predetermined size, it being merely necessary to manually load and eject workpieces in the work turret 70.

It will thus be seen that there has been provided by the invention apparatus in which the various objects hereinabove set forth together with many thoroughly practical advantages are successfully achieved. As many possible embodiments may be made of the above invention and as many changes might be made in the

embodiment above set forth, it is to be understood that all matter hereinbefore set forth, or shown in the accompanying drawings is to be interpreted as illustrative and not in a limiting sense.

I claim:

1. In a grinding machine having a pair of spaced rotatable grinding wheels forming a grinding throat having substantially parallel operative lines of grinding contact, a transversely movable slide movable in a direction parallel to the grinding throat, an indexible work turret thereon located between said wheels, a radially arranged rotatable work support on said turret, said support being arranged normally to support a work piece with its longitudinal axis aligned with the axis of rotation of the work support and its transverse axis in the plane of rotation of said turret, means intermittently to index said turret to move the work support to and from a grinding position and a work support driving mechanism engageable to rotate said support relative to said turret through a partial rotation only when the support is in a grinding position so as to grind partial cylindrical surfaces on opposite edges of a work piece.
2. In a grinding machine having a pair of spaced rotatable grinding wheels forming a grinding throat having substantially parallel operative lines of grinding contact, a transversely movable slide movable in a direction parallel to the grinding throat, an indexible work turret thereon located between said wheels, a radially arranged rotatable work support on said turret, said support being arranged normally to support a work piece with its longitudinal axis aligned with the axis of the work support and its transverse axis in a substantially vertical plane, means intermittently to index said turret to move the work support to and from a grinding position, and a work support driving mechanism arranged to engage and to rotate said support relative to said turret through a partial rotation to shift the transverse axis of the work piece from a vertical to a substantially horizontal plane only when the work support is in a grinding position so as to grind partial cylindrical surfaces on opposite edges of a work piece.
3. In a grinding machine having a pair of spaced rotatable grinding wheels, a transversely movable slide, an indexible work turret thereon located between said wheels, a radially arranged rotatable work support on said turret, said work support being arranged normally to support a work piece with its longitudinal axis aligned with the axis of the work support and its transverse axis in a substantially vertical plane, means to index said turret to hold the work support to and from a grinding position, a work support driving mechanism to rotate said support relative to said turret to shift the transverse axis of the work piece from a vertical to a substantially horizontal position so as to grind partial cylindrical surfaces on opposite edges of a work piece, and means to traverse said turret transversely when the work piece is in a horizontal position to cause a relatively transversing movement between the work piece and the grinding wheels to complete the grinding operation on opposite edges of the work piece.
4. In a grinding machine having a pair of spaced rotatable grinding wheels, a transversely movable indexible work turret between said wheels, a radially arranged rotatable work support on said turret, said support being arranged

normally to support a work piece with its longitudinal axis aligned with the axis of the work support and its transverse axis in a substantially vertical plane, means to index said turret to move the work support to and from a grinding position, a work support driving mechanism to rotate said support so as to shift the transverse axis of the work piece from a vertical to a substantially horizontal position to grind partial cylindrical surfaces on opposite edges of the work piece, and means to traverse said turret transversely to cause a relative reciprocation between the work support and the grinding wheels to complete the grinding operation on opposed edges of a work piece, said driving mechanism serving thereafter to rotate said support in the opposite direction from a horizontal to a vertical position.

5. In a grinding machine, as claimed in claim 4, in which the axes of the grinding wheels are angularly arranged, a frusto-conical face on each of said wheels having substantially parallel elements at the plane of grinding contact for grinding opposite parallel edges on a work piece, and a second frusto-conical face on each of said wheels, the elements of said conical faces on each wheel being at right angles to each other, said second frusto-conical faces serving to grind a shouldered portion on a work piece adjacent to said parallel edges.

6. In a grinding machine having a base, a pair of spaced rotatable grinding wheels forming a grinding throat having substantially parallel operative faces, a transversely movable slide, an indexible turret on said slide which is positioned midway between said wheels, a plurality of normally stationary radially arranged work spindles on said turret, said spindles being arranged normally to support a relatively flat work piece with its longitudinal axis aligned with the axis of the spindle, a clutch between said spindle and the turret normally to hold the spindles against rotation with the transverse axis of the work piece in the plane of rotation of said turret, an indexing mechanism for said turret successively to position said spindles in a grinding position, and a spindle driving mechanism which is movable to an operative position when a work spindle is in a grinding position to disengage said clutch and thereafter to oscillate said spindle through a partial rotation so as to grind partially cylindrical parallel surfaces on opposite edges of the work piece.

7. In a grinding machine, as claimed in claim 6, in combination with the parts and features therein specified in which the transversely movable spindle rotating mechanism includes a rotatable driving spindle, means including a piston and cylinder to move said mechanism to and from an operative position, to engage the driving spindle with the work spindle, means including a piston and cylinder which is operative when a driving spindle is in an operative grinding position to rotate said driving and work spindles in one direction through a partial rotation so as to grind partially cylindrical parallel surfaces on the opposite edges of the work piece, and means to traverse said slide so as to traverse the work piece longitudinally relative to the grinding wheels to grind the remainder of the opposite edges thereon, said driving spindle rotating mechanism serving thereafter to rotate the work spindle in the opposite direction through approximately 90° so as to complete the grinding operation.

8. In a grinding machine, as claimed in claim 6,

in combination with the parts and features therein specified in which the spindle rotating mechanism includes a normally stationary rotatable driving spindle, a transversely movable slide to support said mechanism, means including a piston and cylinder to move said slide to and from an operative position, means including a piston and cylinder which is operative when a work spindle is in a grinding position to rotate said driving and work spindles in one direction through a partial rotation so as to grind partially cylindrical parallel surfaces on the opposed edges of a work piece, and means including a piston and cylinder to traverse said slide so as to traverse the work piece longitudinally relative to the grinding wheels to grind the remainder of the edges thereon, said spindle rotating piston and cylinder serving thereafter to rotate said spindle in the opposite direction through approximately 90° so as to complete the grinding operation.

9. In a grinding machine having a base, a pair of spaced rotatable grinding wheels forming a grinding throat having substantially parallel operative faces, a transversely movable slide, a piston and cylinder to move said slide, an indexible turret on said slide which is positioned between said wheels, a plurality of normally stationary radially arranged work spindles rotatably mounted on said turret, said spindles being arranged normally to support a work piece with its longitudinal axis in the plane of rotation of the turret, an indexing mechanism including a fluid motor for said turret successively to move said spindles to and from a grinding position, a normally inoperative spindle driving mechanism which is operative when a spindle is in a grinding position to engage and drive said spindle through approximately 90° so as to grind partially cylindrical parallel surfaces on the opposite edges of the work piece.

10. In a grinding machine having base, a pair of opposed spaced grinding wheels forming a grinding throat having substantially parallel operative faces, a transversely movable slide, and indexible turret on said slide which is positioned between said wheels, a piston and cylinder to move said slide, a plurality of normally stationary radially arranged work spindles rotatably mounted on said turret, said spindles being arranged normally to support a work piece with its longitudinal axis aligned with the axis of the spindle and its transverse axis in a substantially vertical plane, and indexing mechanism including a fluid motor for indexing the turret successively to move said spindles to and from a grinding position, a notched index plate, a spring pressed pawl successfully to locate said turret in predetermined index positions, a piston and cylinder to withdraw said pawl, a transversely movable slide on said first slide, a normally inoperative driving spindle thereon, a piston and cylinder to move said second slide to position the driving spindle in driving engagement with the work spindle when the latter is in an operative position, and a piston and cylinder to rotate the driving spindle through a partial rotation so as to swing the transverse axis of the work piece from a vertical to a horizontal position to grind partial cylindrical surfaces on opposite edges of a work piece.

11. In a grinding machine, as claimed in claim 10, in which a control valve serves to control the admission to an exhaust of fluid from the pawl cylinder to control withdrawal of said pawl to initiate a turret indexing movement, a second

control valve to control the admission of fluid to the index motor, a third control valve to control the exhaust of fluid from the index motor, and a fourth control valve to control the admission to an exhaust of fluid from the work driver slide cylinder, the work driver rotating cylinder and the turret slide cylinder so as to control the grinding operation.

12. In a grinding machine, as claimed in claim 10, in which a solenoid-actuated control valve serves to control the admission to an exhaust of fluid from the pawl cylinder to control withdrawal of said pawl to initiate a turret indexing movement, a second solenoid-actuated control valve to control the admission of fluid to the index motor, a third solenoid-actuated control valve to control the exhaust of fluid from the index motor, a fourth solenoid-actuated control valve to control the admission to an exhaust of fluid from the work driver slide cylinder, the work driver rotating cylinder and the turret slide cylinder, an electric timer, a switch actuated by and in timed relation with the indexing movement of said turret to start said timer, said timer serving after a predetermined time interval to deenergize said fourth solenoid-actuated control valve to terminate the grinding operation.

13. In a grinding machine, as claimed in claim 10, in which a solenoid-actuated control valve serves to control the admission to and exhaust of fluid from the pawl cylinder to control withdrawal of said pawl to initiate a turret indexing movement, a second solenoid-actuated control valve to control the admission of fluid to the in-

dex motor, a third solenoid-actuated control valve to control the exhaust of fluid from the index motor, a fourth solenoid-actuated control valve to control the admission and exhaust of fluid from the work driver slide cylinder, the work driver rotating cylinder and the turret slide cylinder, a switch actuated by movement of the pawl to an inoperative position to deenergize the first solenoid-actuated control valve to start the fluid motor and thereby initiate an indexing movement of the work turret, an electric timer, a switch actuated by and in timed relation with the indexing movement of the turret to start said timer, said timer serving after a predetermined time interval to deenergize said fourth solenoid-actuated control valve to terminate grinding operation.
